UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed December 13, 1926. Serial No. 154,431.

My invention relates to car roofs and has for its principal object to produce a simple and economical construction that is easy of application and that will readily adapt itself to the distortions of the car body incident to service conditions. The invention consists in the parts and in the combinations and arrangements of parts hereinafter described and claimed.

10 In the accompanying drawings, which form part of this specification and wherein like symbols refer to like parts wherever they occur,

Fig. 1 is a plan view of a portion of a car roof embodying my invention;

Fig. 2 is a vertical cross-section through one-half of the roof on the line 2—2 in Fig. 1;

Fig. 3 is a vertical cross-section through one of the roof seams at the ridge on the line 3—3 in Fig. 2;

Fig. 4 is a similar cross section intermediate the ridge and eaves on the line 4—4 in Fig. 2;

25 Fig. 5 is a fragmentary plan view showing the socket connections between the ridge portions of adjacent carlines and the sheet located therebetween;

Fig. 6 is a fragmentary plan view of the 30 ridge portion of a carline of modified construction; and

Fig. 7 is a vertical cross-section on the line 7—7 in Fig. 6.

The present roof comprises Z-bar side 35 plates 8 that are connected by carlines 9 of substantially inverted channel-shaped section with outwardly projecting lateral base flanges 10 at the bottoms of their side walls. The Z-bar side plates 8 are preferably arranged with their webs vertical and with their top flanges extending inwardly horizontally; and the eaves end portions of said carlines 9 rest flatwise on the inwardly projecting top flanges of said side plates and 45 have their lateral base flanges 10 rigidly secured thereto by rivets 11.

Metal roof sheets 12 extend from eaves to eaves of the car between adjacent carlines and are of less width than the spaces between 50 the inverted channel-shaped body portions thereof. Said roof sheets are supported at the eaves preferably on wooden filler strips

13, which extend from carline to carline and rest on and are rigidly secured to the top flanges of the side plates by bolts 14. The 55 roof sheets are also supported between the ridge and the eaves, preferably by means of purlins 15, which extend longitudinally of the car beneath the carlines and are bolted or otherwise rigidly secured to the lateral base flanges thereof. The roof sheets are 60 provided at their eaves ends with depending flanges 16, which overhang and are spaced from the webs of the side plates. The roof sheets are supported on the filler strips 13 and purlins 15 above the plane of the base flanges of the carlines and have upwardly offset side marginal portions 17 that are inclined upwardly and terminate in upstanding side marginal seam flanges 18 that extend from end to end of said sheets.

The roof sheets are loosely connected along their adjacent side margins by weatherproofing seam covers or caps 19 of substantially inverted channel-shaped section which straddle the carlines 9 and the upstanding side marginal seam flanges 18 of adjacent sheets, 75

the side walls of said seam covers and said seam flanges being normally spaced apart from end to end of the sheets. As shown in the drawing, the webs of the inverted channel-shaped seam covers 19 rest flatwise on the webs of the inverted channel-shaped carlines 9 and are rigidly secured thereto at points adjacent to the ridge and eaves by 80 rivets 20. The seam covers 19 are provided, along the lower edges of their side walls with outwardly projecting lateral base flanges 21 that conform to the slope of the upwardly offset side marginal portions 17 85 of the roof sheets and are arranged to rest or bear flatwise on said portions, thereby holding said sheets down on the car. The eaves end portions of the seam covers 19 are provided with depending eaves flanges 22, 90 which overlap the open ends of the carlines 9 and the end portions of the depending eaves flanges 16 of adjacent sheets and are spaced away from said eaves flanges.

Running boards 23 extend longitudinally 100 of the car at the ridge and are supported on the lateral top flanges of Z-bar running board saddles 24, whose lateral base flanges rest on the ridge portions of the seam covers

19 and are rigidly secured in position by the rivets 20 that secure the ridge portions of said seam covers to the carlines 9.

Riveted or otherwise rigidly secured to the under side of each roof sheet at the ridge is a stiffening member comprising a strip of sheet metal 25, which extends transversely of the sheet with its end portions supported on the opposing base flanges of adjacent carlines and bent up beyond the side margins of the sheet to form upstanding end flanges 26. The stiffening members are provided with longitudinal stiffening ribs 27 that terminate short of their end flanges 26. The end flanges 26 of the sheet stiffeners are bowed or curved outwardly from side to side to form convex surfaces 28 at the ends of said members; and the portions of the side walls of the carlines located opposite the convex ends of said sheet stiffeners are longitudinally curved or bowed inwardly toward each other to form in the outside faces of said carlines concave depressions or sockets 29 adapted to receive the ends of said stiffeners. As shown in the drawings, the convex ends of the stiffening members and the concave sockets of the carlines have substantially the same radius of curvature and are curved in circular arcs described from the centers of the sheets.

In the modified construction illustrated in Figs. 6 and 7, the carline 9^a is of full width at the ridge, and a pivot clip 30 of inverted channel-shaped section straddles the carline at the ridge and has its side flanges bowed inwardly to form curved recesses or sockets 29^a for the convex ends 28 of the sheet stiffening members 25.

By the arrangement described, the socket connections between the sheet stiffening members and the carlines enable the roof sheets to accommodate themselves automatically to the distortions of the car body by forcing the sheets to pivot or slue about points located at their centers. The socket joints or connections between the opposing faces of adjacent carlines and the convex ends of the sheet stiffeners serve to prevent bodily movement of the sheets both longitudinally and transversely of the car and thus normally maintain a proper clearance between the eaves flanges of the sheets and the side plates and between the sides of the sheets and the seam covers and carlines. The sheet stiffening members rest on the opposing base flanges of adjacent carlines and thus serve to support and stiffen the sheets at the ridge, while the upturned end flanges of said members abut against the opposing sides of adjacent carlines and thus serve as struts or braces to maintain a proper spacing of the carlines at the ridge.

The invention is not limited to the precise shapes and arrangements of parts shown and described. For instance, the radii of

the convex ends of the sheet stiffeners may be less than the radii of the concave sockets in the carlines; also, the radii of said concave sockets may be longer than the distance between the centers of the sheets and said sockets.

What I claim is:

1. In a car roof having a substructure comprising spaced members, and roof sheets between said members, means on each sheet permitting said sheet to rotate substantially on its center and means on the adjacent members of said substructure engaging the sheets. 75

2. In a car roof having a substructure comprising spaced members, and roof sheets between said members, means on each sheet permitting said sheet to rotate about a point located intermediate adjacent members and means on adjacent members engaging the sheets. 85

3. A car roof comprising carlines extending from side plate to side plate, and roof sheets arranged in the spaces between said carlines, means on the sheet permitting said sheet to rotate substantially on its center and means on the adjacent carlines engaging the sheets. 90

4. A car roof comprising carlines extending from side plate to side plate, and roof sheets arranged in the spaces between said carlines, means on the sheet permitting said sheet to rotate to a point located substantially midway of adjacent carlines and means on the adjacent carlines engaging the sheets and preventing bodily movement thereof. 95

5. A car roof comprising carlines extending from side plate to side plate, and roof sheets arranged between adjacent carlines having socket connections therewith adapted to secure an independent pivotal movement of said sheets between carlines and to prevent bodily movement of said sheets both longitudinally and transversely of the car. 105 110

6. A car roof comprising carlines extending from side plate to side plate, and roof sheets arranged between adjacent carlines, said carlines and said roof sheets having interfitting longitudinally bowed portions. 115

7. A car roof comprising carlines extending from side plate to side plate, and roof sheets arranged between said carlines, the sides of the sheets located adjacent to said carlines being provided with convex portions and the sides of the carlines being provided opposite said convex portions with concave recesses adapted to cooperate therewith. 120

8. A car roof comprising carlines extending from side plate to side plate and having concave recesses in their side faces, roof sheets disposed between said carlines, and members secured to said sheets and having convex ends fitting the concave recesses in said carlines, the concave recesses in said car- 125 130

- lines and the convex ends of the members secured to the sheets being curved in circular arcs described from points located substantially midway of adjacent carlines.
5. 9. A car roof comprising carlines extending from side plate to side plate, roof sheets arranged between said carlines, said carlines having concave recesses in their side faces, and members secured to said sheets and supported on said carlines, said members having convex end portions adapted to turn in the concave recesses in said carlines.
10. A car roof comprising carlines extending from side plate to side plate, roof sheets 15 extending from side plate to side plate between carlines, the ridge portion of the side faces of said carlines being provided with concave surfaces, and members secured to the under sides of said sheets at the ridge 20 and extending longitudinally of the roof with their ends supported on said carlines, said members having convex ends that fit concave surfaces of said carlines.
11. A car roof comprising carlines extending from side plate to side plate, roof sheets 25 extending from side plate to side plate between carlines, the sides of said carlines being provided at the ridge with concave surfaces, and members secured to the under 30 side of the roof sheets at the ridge and extending from carline to carline with their ends resting thereon, said members being provided at their ends with flanges that are curved to fit the concave surfaces of said carlines.
35. 12. A car roof comprising carlines extending from side plate to side plate, roof sheets
- extending from side plate to side plate between carlines, clips straddling the carlines at the ridge and having concave recesses in their side faces, and members secured to the under sides of the sheets at the ridge and extending longitudinally of the roof with their ends supported on said carlines, said members having convex ends that fit the concave recesses in said clips. 40
13. A car roof comprising carlines extending from side plate to side plate, roof sheets arranged between said carlines, and members secured to said roof sheets and movably supported on said carlines. 45
14. A car roof comprising carlines extending from side plate to side plate, said carlines being of substantially inverted channel-shaped section with outstanding base flanges 50 at the lower edges of their side walls, roof sheets extending from side plate to side plate between carlines, and stiffening members secured to the under sides of said sheets at the ridge, said members extending from carline 55 to carline with their ends movably supported on the base flanges thereof.
15. A car roof sheet comprising a body portion and a stiffening member secured to said body portion, said member having convex surfaces at its ends. 60
16. A car roof sheet comprising a body portion and a sheet metal stiffening member rigidly secured to said body portion, said member having end flanges that are bowed 65 outwardly from side to side. 70

Signed at New Kensington, Pa., this 4th day of December, 1926.

CHARLES DAVID BONSALL.
